UNITED STATES PATENT OFFICE.

RUDOLPH CONRADER, OF ERIE, PENNSYLVANIA.

UNLOADER FOR COMPRESSORS.

1,239,566.

Specification of Letters Patent. Patented Sept. 11, 1917.

Application filed May 4, 1915. Serial No. 25,855.

To all whom it may concern:

Be it known that I, RUDOLPH CONRADER, a citizen of the United States, residing at Erie, in the county of Erie and State of Pennsylvania, have invented new and useful Improvements in Unloaders for Compressors, of which the following is a specification.

This invention relates to unloaders for compressors and consists in certain improvements in the construction thereof as will be hereinafter fully described and pointed out in the claims.

More particularly the invention relates to improvements of the unloader described in patent issued to me June 28th, 1910, #962,551.

The invention is illustrated in the accompanying drawing which shows a central section of the unloader.

1 marks the body of the valve, 2 the diaphragm having the valve opening and seat, 3 the valve, 4 and 5 the inlet and discharge ends of the valve, either end may be the inlet. A frame 6 extends from the body 1 and a cylinder 7 is arranged in this frame. A piston 8 operates in the cylinder 7 and is connected with the valve by means of a stem 9. The stem extends through a spider 30 or plate 10 having openings so that the shell or frame 6 and cylinder 7 are in communication with one end. A spring 11 is arranged around the stem 9 between the plate 10 and a shoulder on the stem.

35 A receiver connection 12 leads to the cylinder 13. A piston 14 is arranged in the cylinder 13. Its movement under pressure is opposed by a spring 15 and the spring 15 may be adjusted by a screw 16. The piston 40 carries a needle valve 17 operating in a passage 18. The passage 18 leads to the intensifying chamber 19 from which leads a minute opening 20. The device just described operates as an intensifier along the 45 manner described in my former patent. Slight variations of receiver pressure move the piston 14 giving to the needle valve 17 various degrees of opening. With a slight opening of the needle valve the escape of 50 air through the minute opening is such as to make a low pressure in the intensifying chamber somewhat above atmosphere. As the opening past the needle valve is increased it reaches a point where the opening 55 20 has little influence on the total pressure so that approximately receiver pressure will

be delivered to the intensifying chamber under these conditions. This gives a wide range of pressure in the intensifying chamber for a small variation of pressure in the receiver.

In my former structure, the air was delivered to the intensifier directly on the piston 8. In that device the air was passed through the valve either from the end 5 65 when an abrupt closing was desired or from the end 4 when a regulating effect was desired. Under some circumstances, as for instance, with low pressure, it may be desirable to have an abrupt closing but where 70 the device of my former patent was used, when the valve 3 closed the atmospheric pressure alone on the valve with nearly a vacuum under the valve was sufficient to retard the opening of the valve before the 75 pressure in the cylinder 7 was reduced practically to atmospheric pressure, the reason for this being that the spring 11 cannot be of greater strength or stiffness than can be operated by the air on the piston 8. The 80 air discharging from the piston 7 through the minute opening 20 is very slow and where a nice regulation especially with a small receiver is required interferes with the nice regulation of pressure. This is 85 true where either the end 4 or the end 5 is used, as an inlet.

In the present invention I introduce an intermediate pressure controlled valve 22. This is arranged in a cylinder 23. The cylinder 23 is connected with the intensifying chamber 19 by a passage 21 so that the pressure of the intensifying chamber is delivered to one end of the valve 22. A spring 24 opposes the movement of the valve 22 and 90 the spring may be adjusted by a screw 25. The passage 26 connects the cylinder 23 with the cylinder 7. The valve 22 has a central way 27 which normally communicates with the passage 26. The exhaust passage 28 100 leads from the cylinder 23 and this passage is normally in communication with the way 27. The exhaust passage is open to the atmosphere and the size of the opening may be adjusted by a screw 29.

In the operation of the device when the receiver pressure reaches the desired amount it begins to open the valve 17. As the pressure accumulates in the intensifying chamber 19 and the receiver pressure increases, 110 the pressure on the valve 22 finally becomes sufficient to move the valve 22 sufficiently to

uncover the passage 26. This movement closes off the passage 26 from the way 27. As soon as the passage 26 is uncovered air is delivered directly to the piston 8 and the valve is closed. When the pressure diminishes so as to permit the valve 22 to close, the passage 26 is brought into communication with the way 23. The enlarged exhaust passage permits of the immediate 10 exhaust from the cylinder 8 so as to effect the opening of the valve 3.

What I claim as new is:—

1. In an unloader for compressors, the combination of a valve body having inlet and discharge openings and a valve seat therein; a valve operating on said seat; a fluid actuated motor controlling said valve; a pressure actuated valve controlling said motor; a cylinder in which the pressure actuated valve operates, said cylinder having an inlet port admitting fluid to the end of the valve and subjecting the valve to the pressure therefrom; a port leading to the fluid actuated motor and the exhaust port, 20 said port leading to the fluid actuated motor being covered by the valve as it is operated and being connected as the valve is operated with either the inlet port or the exhaust port; counterpressure means opposing the 25 movement of the valve; a needle valve controlling said inlet port; and a pressure motor controlling said needle valve.

2. In an unloader for compressors, the combination of a valve body having inlet and discharge openings; and a valve seat; a relief valve opening and closing by a movement toward and from its seat; a fluid actuated motor controlling said valve; a pressure actuated valve controlling said motor, 30 said valve having a pressure passage and an

exhaust passage controlled by the valve; and an intensifier connected with said pressure actuated valve and controlling the delivery of air to said pressure actuated valve said intensifier comprising a chamber; a 45 gradually opening needle valve controlling the admission of fluid to said chamber; and a minute discharge opening from said chamber.

3. In an unloader for compressors, the combination of a valve body having inlet and discharge openings and a valve seat therein; a valve operating on said seat; a fluid actuated motor controlling said valve; a pressure actuated valve controlling said motor; a cylinder in which the pressure actuated valve operates, said cylinder having an inlet port admitting fluid to the end of the valve and subjecting the valve to the pressure therefrom; a port leading to the fluid actuated motor; and an exhaust port, 50 said port leading to the fluid actuated motor being covered by the valve as it is operated and being connected as the valve is operated with either the inlet port or the exhaust port; counter-pressure means opposing the 55 movement of the valve; and an intensifier controlling the movement of air to the inlet port, said intensifier comprising a chamber; a gradually opening needle valve controlling the movement of fluid to the chamber; and a minute discharge opening leading 60 from the chamber.

In testimony whereof I have hereunto set my hand in the presence of two subscribing 70 witnesses.

RUDOLPH CONRADER.
